UNITED STATES PATENT OFFICE.

JOSHUA W. BRADY, OF ST. PAUL, MINNESOTA.

LOOSE-LEAF HOLDER.

Application filed January 31, 1922. Serial No. 533,064.

To all whom it may concern:

Be it known that I, JOSHUA W. BRADY, a citizen of the United States, residing at St. Paul, in the county of Ramsey and State of Minnesota, have invented a new and useful Loose-Leaf Holder, of which the following is a specification.

My invention relates to loose leaf holders of the kind adapted to be supported either 10 on a desk or table or by one of the operator's hands and firmly yet detachably holds one or more sheets to be written on, and the object is to improve such a device by new parts and features as will now be described.

15 In the accompanying drawing,—

Fig. 1 is a perspective view of my improved loose leaf holder partly opened and with loose leaves placed on it ready to be secured.

20 Fig. 2 is an edge view of the device in unfolded but idle position.

Fig. 3 is an edge view of the device as it appears just after some loose leaves have been secured in it.

25 Fig. 4 is Fig. 3 with the upper cover turned upon the back of the lower cover and showing also how leaves written on may follow the top cover and thus be out of the way for further writing on the remaining sheets.

30 Fig. 5 is an enlarged section on line 5—5 in Fig. 3.

Fig. 6 is an enlarged edge view of the part of the device containing clasping springs for holding the loose sheets.

35 Fig. 7 is a plan view of the outer side of the sliding sleeve modified.

Referring to the drawing by reference numerals, 10 designates the usual flat, stiff body, upon which the leaves 11 to be written 40 on, are placed. In the curved head end 12 of said body are imbedded leaf springs 13 (see dotted lines in Fig. 6) which may be of any desired curvature, so that each of them forms a lower clasping arm 14 and an 45 upper clasping arm 15. The latter arm tends at all times to close the upper part or jaw 12^a down against the body plate 10 and hold leaves 11 inserted between them.

50 16 is a flat, stiff cover adapted to rest upon the leaves 11 to protect them when the device is not in actual use.

In some of the devices of this class heretofore used the cover 16 is hinged at 17 to the jaw 12^a, so that when the cover is 55 swung to the position shown in Fig. 3 it

can be used as a lever to force the jaw 12^a open while the paper 11 is being inserted under it upon the body 10 and by releasing the cover the jaw will of course 60 pinch and hold the paper. But the objection to this structure is that the stiff, heavy cover 16 will have to remain in an awkward and obstructive position during the use of the device. To overcome this attempts have 65 been made to give the cover several additional joints 18, 19, by which to enable the cover 16 to be folded backward and up under the body 10 as shown in Figs. 2 and 4. But these joints 18, 19, render the 70 cover unfit to act as a lever in opening the jaw 12^a.

To overcome the last mentioned difficulty I provide the cover with a flat, slidable sleeve 20, which may be open as at 21 or 75 solid as at 22 in Fig. 7 upon the back of the cover 16. The object of making it solid is to stiffen the sleeve so it will support the entire cover section 16 and thus not allow the middle of it to bulge down toward 80 the leaves 11.

In Fig. 5 line 23 shows how the inward side of the sleeve may be sprung away from the cover while leaves already written on may be inserted between the sleeve and 85 the cover, as at 24 in Fig. 4 clear away from the leaves to be written on. Where this holding of the written sheets is not desired the leaves may be removed from the device.

90 In the use and operation of the device the sleeve 20 occupies the position shown in Fig. 3 only while the cover is used or ready to be used as a lever for opening clasping jaw 12^a, and is then slid over onto the 95 main section 16 of the cover to allow the joints 18—19 to bend in folding the cover upon the back of the body 10.

Having thus described my invention, what I claim is:

100 1. A loose leaf holder comprising in combination a flat body for the loose leaves to rest on, said body having at one end an upwardly and inwardly curved resilient jaw for holding the loose leaves against the 105 body, a cover hingedly connected with the jaw and adapted to rest upon the body and the leaves thereon, said cover adapted to lean upon the jaw and act as a lever in forcing it open, said cover having also near 110 said jaw joints enabling it to be folded over the jaw and upon the under side of

the body, and a flat sleeve slidable on the cover and adapted to cover said joints and prevent their bending while the cover is being used as a lever.

5. 2. The structure specified in claim 1, said sleeve adapted also to hold the written leaves folded away to the bottom side of the body.

10 3. The structure specified in claim 1, said sleeve being partly cut away at the upper side of the cover so as to save material in making it.

4. A loose leaf holder comprising a flat body for the loose leaves to rest on, said

body having at one end a spring-pressed 15 jaw adapted to hold the leaves upon the body, a cover hinged to the swinging end of the jaw and adapted to protect the leaves, said cover having joints enabling it to be bent over the jaw and thus folded in under the body, and a flat sleeve slidable on the cover and adapted to prevent bending of said joint while the cover is being used as a lever for opening the jaw.

20 25 In testimony whereof I affix my signature.

JOSHUA W. BRADY.
